UNITED STATES PATENT OFFICE.

JULIAN B. JENSEN, OF ALAMEDA, CALIFORNIA.

PUMP.

1,406,868.

Specification of Letters Patent. Patented Feb. 14, 1922.

Application filed May 6, 1920. Serial No. 379,225.

To all whom it may concern:

Be it known that I, JULIAN B. JENSEN, a citizen of the United States, and a resident of Alameda, county of Alameda, and State 5 of California, have invented a new and useful Pump, of which the following is a specification.

My invention relates to pumps of the centrifugal and turbine type.

10 An object of the invention is to provide a pump of the centrifugal type through which the liquid is enabled to flow without entailing the usual excessive friction.

Another object of the invention is to provide 15 a pump in which is effected the complete neutralization of the end thrust of the revolving parts.

A further object of the invention is to provide 20 a centrifugal pump in which a large volume of fluid is enabled to be directly and continuously introduced into the impeller adjacent the base of its vanes.

The invention possesses other objects and 25 features of advantage, some of which with the foregoing, will be set forth in the following description of the preferred form of my invention which is illustrated in the drawings accompanying and forming a part of the specification. It is to be understood that 30 I do not limit myself to the showing made by the said drawings and description as I may adopt variations of the preferred form within the scope of my invention as set forth in the claims.

35 Referring to said drawings;

Fig. 1 is a vertical transverse section of the pump.

Fig. 2 is a vertical longitudinal section of 40 pump, the plane of section being indicated by the line 2—2 of Fig. 1.

Fig. 3 is a side elevation of the impeller and guide blades, parts thereof being broken away and shown in section to disclose the construction.

45 Fig. 4 is an inside end elevation of one of the casing end sections.

Briefly expressed the pump of my invention comprises a casing having a pair of suction chambers in which are disposed a 50 plurality of guide passages that are adapted to introduce the fluid into the impeller axially and in the direction of rotation thereof. The impeller is also of novel construction and with the aid and cooperation 55 of said passages a very efficient delivery of the fluid may be effected.

A detailed description of my invention follows:

The pump comprises a casing 5 consisting of two end sections 6 and 7 and a middle 60 section 8 all of which are suitably bolted together.

Extending through said sections and mounted for rotation in the bearings 9 is the pump shaft 11 upon which is fixed the impeller 12. The end sections 6 and 7 are disposed in substantially concentric relation with respect to the shaft and form suction chambers 13 and 14. The middle section 8 is preferably of involute form and includes 70 a delivery chamber 16 and a suction inlet 17 which communicates with both suction chambers 13 and 14 through means of the openings 18 and 19.

The impeller which in the present form of 75 the invention is disposed in the delivery chamber, intakes at both ends, and by referring to Fig. 2 it will be noted the opposing ends of the chamber 16 are open, so that both intake ends of the impeller communicate 80 with the suction chambers. In this manner, assuming equal areas and openings on opposite ends of the impeller, the end thrust of the rotating parts will be practically neutralized, thereby reducing the 85 wear on the pump parts materially.

As shown in Fig. 1, the impeller comprises a plurality of curved radial vanes 21 which are provided with walls 22 and 23 at the opposite ends thereof. The end walls 22 90 and 23 of each vane preferably terminate a short distance behind the rear face of the preceding vane thus providing a plurality of intake openings 24 and 25 at each end of the impeller. The opposed end walls of 95 each vane converge in the direction of the tip of the vane with which they are associated. In this manner the fluid which enters the impeller from its opposite ends is not only subjected to a centrifugal force due to 100 the rotation of the vanes, but is gradually brought into closer association prior to its exit from the impeller; in other words the opposed streams which enter the impeller are discharged therefrom in the form of a 105 single forceful jet.

Means are provided, which cooperate with the end walls of the vanes, to cause the fluid to be forcibly drawn into the impeller and to impinge directly upon the rear face and base 110 of the vanes thereof. Fixed in the suction chambers, adjacent each end of the impeller

and axially aligned therewith are a plurality of guide blades 27 defining a plurality of fluid guide passages 28. Each of the blades is substantially segmental in form and is preferably disposed about the pump axis in the form of a short helix. Furthermore the blades are arranged in such a manner that the jets of fluid issuing from the guide passages will be directed in the direction of rotation of the adjacent portion of the impeller. Accordingly, referring to Figure 1 in which the pump shaft rotates in the direction indicated by the arrows, the guide blades 29 at the left of the impeller will be disposed in dextrorsal relation, while the blades 31 at the right of the impeller will be disposed in sinistrorsal relation.

As has been heretofore mentioned the end walls 22 and 23 converge in the direction of the tips of the vanes, or in other words the walls 22 adjacent the dextrorsal blades are disposed in sinistrorsal relation, while the walls 23 adjacent the sinistrorsal blades are disposed in dextrorsal relation. Referring now more particularly to Figure 3 it will be clearly understood that when the end walls, which broadly speaking, function as pump blades, sweep by the guide blades, the partial vacuum existing between the vanes is considerably augmented, thereby causing the entire amount of fluid issuing from the guide passages to be quickly drawn into the impeller. Furthermore as aforementioned the streams of the fluid enter the impeller in the direction of rotation thereof, so that the fluid prior to being acted upon by the vanes has already attained the motion which the vanes are to impart to it. In this manner part of the work, ordinarily performed by the impeller, is done through the agency of the guide blades, thereby enabling the former to perform its work more efficiently and to act upon a greater amount of fluid.

I claim:

1. A pump comprising a casing having a suction and a delivery chamber, an impeller rotatably mounted therein, a radially disposed vane and a dextrorsally disposed end plate formed on said impeller, and a sinistrorsally disposed passage in the suction chamber adjacent said impeller.

2. A pump comprising a casing having a suction and discharge chamber, an impeller rotatably mounted therein, a radially disposed vane and a sinistrorsally disposed end plate formed on said impeller, and a dextrorsally disposed passage in said suction chamber adjacent said impeller.

3. A pump comprising a casing having a suction chamber, an impeller rotatably mounted in said casing and communicating with said chamber at opposite ends, a dextrorsally disposed end wall and a sinistrorsally disposed end wall formed on said impeller, a radially disposed vane formed be-

tween and connecting said end walls, and a sinistrorsally disposed guide passage and a dextrorsally disposed guide passage arranged in said suction chamber adjacent said dextrorsally disposed end wall and sinistrorsally disposed end wall respectively.

4. A pump comprising an involute casing having a suction and a delivery chamber, an impeller rotatably mounted in said casing and communicating at its opposite ends with said suction chamber, a plurality of curved radial vanes formed in said impeller, converging walls formed on opposite ends of said vanes adjacent their tips, a plurality of dextrorsally disposed fluid guide passages arranged in said suction chamber adjacent one of said end walls, and a plurality of sinistrorsally disposed fluid guide passages arranged in said suction chamber adjacent the other of said end walls.

5. A pump comprising a casing having a suction chamber and an involute delivery chamber, an impeller rotatably mounted in said casing having its sides and opposite ends in communication with the delivery and suction chambers respectively, a plurality of outwardly curved radial vanes formed on said impeller, walls extending outward radially from the opposite ends of said vanes and converging in the direction of the vane tips, said walls being omitted adjacent the rear face of the vanes, dextrorsally disposed guide blades fixed in said suction chamber adjacent one end of said vanes, and sinistrorsally disposed guide blades disposed in said chamber adjacent the other end of said vanes.

6. A pump comprising a casing having an involute delivery chamber formed centrally therein, a suction chamber formed on opposite ends of said delivery chamber, an impeller rotatably mounted within said delivery chamber and communicating at opposite ends with said suction chamber, radial vanes formed on said impeller, walls formed at the opposite ends of said vanes and converging in the direction of the vane tips, said walls being omitted adjacent the base of said vanes to provide end openings in the impeller, a plurality of spaced dextrorsally disposed blades fixed in the suction chamber adjacent one end of said impeller and defining a set of radially disposed guide passages adapted to register with the openings in said end of the impeller, and a plurality of spaced sinistrorsally disposed blades fixed in the suction chamber adjacent the other end of said impeller and defining a set of radially disposed guide passages adapted to register with the openings in said last mentioned end of the impeller.

7. A pump comprising a casing having a suction and delivery chamber, an impeller rotatably mounted in said casing, inclined passages in said suction chamber adapted to 130

guide the fluid to said impeller in the direction of rotation thereof, and an end wall on said impeller inclined reversely of said passages.

- 5 8. A pump comprising a casing having a suction and delivery chamber, an impeller rotatably mounted in said casing, inclined passages in said suction chamber adapted to guide the fluid to said impeller in the direction of rotation thereof, blades on said

impeller, and an end wall on said impeller extending from one side of each blade toward the adjacent side of the next blade, said wall being spaced from said latter blade from the base to substantially the outer edge 15 thereof.

In testimony whereof, I have hereunto set my hand at Oakland, California, this 7th day of April, 1920.

JULIAN B. JENSEN.
